UNITED STATES PATENT OFFICE.

ADOLF GUND, OF NEW YORK, N. Y.

ANIMATED TOY.

1,146,700.

Specification of Letters Patent. Patented July 13, 1915.

Application filed December 9, 1914. Serial No. 876,282.

To all whom it may concern:

Be it known that I, ADOLF GUND, a subject of the German Emperor, and a resident of the city of New York, borough of the Bronx, in the county of Bronx and State of New York, have invented a new and Improved Animated Toy, of which the following is a full, clear, and exact description.

The invention relates to spring motor actuated toys, and its object is to provide a new and improved animated toy, preferably simulating a human being or an animal, and arranged to creep or walk along a floor, table or other support.

In order to accomplish the desired result, use is made of a driven crank shaft and four angular levers having depending members and longitudinal members, the latter being pivotally connected with the cranks of the said shaft, the levers being mounted to swing and to slide on fixed pivots, and the depending members of the said levers being adapted to travel on a floor, table or other support.

A practical embodiment of the invention is represented in the accompanying drawings forming a part of this specification, in which similar characters of reference indicate corresponding parts in all the views.

Figure 1 is a perspective view of the animated toy simulating a creeping baby; Fig. 2 is a similar view of the animated toy simulating a walking animal; Fig. 3 is an enlarged side elevation of the actuating mechanism with one side of the frame or casing removed; Fig. 4 is a sectional side elevation of the same on the line 4-4 of Fig. 5; and Fig. 5 is a sectional plan view of the same on the line 5-5 of Fig. 4.

The hollow body A of the animated toy may be of any approved shape, for instance, as shown in Fig. 1, the said body A simulates a creeping baby having articulated arms A' and bent legs A², of which the hands are approximately spread out horizontally and extend in the same plane with the knees of the legs, and the hands and knees are preferably provided at the under side with rubber pads A³, A⁴, adapted to contact with a floor, table or other surface along which the baby is to creep. The hollow body A, as shown in Fig. 2, simulates a walking animal having articulated front legs A⁵ and hind legs A⁶, preferably provided at the soles of the feet with rubber pads A⁷ and A⁸, adapted to contact with

a floor, table or other surface along which the animal is to walk.

Within the hollow body A of the animated toy is secured a frame or casing B, provided with a central compartment B' and two side compartments B², and in the rear end of the said frame or casing B is journaled a winding-up shaft C for winding up a spring D secured at its inner end to the said shaft C and fastened at its outer end to the bottom of the frame or casing B. One end of the shaft C extends through the corresponding side of the body A to the outside of the latter, and the outer end of this shaft C is made polygonal for the application of a key E to permit of turning the shaft C with a view to wind up the spring D.

The spring D is located in the central compartment B' of the frame or casing B and on the shaft C adjacent the said spring is secured a gear wheel F in mesh with a pinion F' secured on a transversely extending crank shaft G provided at its ends with crank arms G' and G² extending within the side compartments B² of the frame or casing B. The crank arms G' and G² are connected with longitudinal members H' of levers H having depending members H² to which the arms A' of the baby or the front legs A⁵ of the animal are secured. Each lever H is provided with an upwardly and rearwardly inclined slot H³ engaged by a pivot pin I secured to the casing B within the corresponding outer compartment B². The crank arms G' and G² are also pivotally connected with longitudinal members J' of levers J having depending members J² attached to the legs A² of the baby or the rear legs A⁶ of the animal. The upper end of each lever J is provided with a forwardly and upwardly extending slot J³ into which projects a pivot pin I' attached to the frame or casing B within the corresponding outer compartment B². The members H² and J² of the levers H and J extend through slots B³ formed in the bottom of the casing B to guide the said members H² and J² during their forward and backward movement, as hereinafter more fully explained. The depending members H² and J² are slightly bent outwardly so as to give the desired stability to the animated toy.

In order to check the rotary movement given to the crank shaft G from the spring-pressed winding-up shaft C, use is made of a checking device which is preferably in the

form of a train of gear wheels, of which the first gear wheel K is secured on the shaft G within the central compartment B', and the said gear wheel K is in mesh with a pinion K' secured on a shaft K² journaled on the frame or casing B. On the shaft K² is secured a gear wheel K³ in mesh with a pinion K⁴ secured on a transverse shaft K⁵ journaled in the frame or casing B, and on the shaft K⁵ is secured a gear wheel K⁶ in mesh with a pinion K⁷ secured on a transverse shaft K⁸ journaled in the casing B. It will be noticed that when the spring D is wound up by the key E and the latter is released or removed then the shaft C is rotated and drives the crank shaft G in the direction of the arrow a', so that the crank arms G' and G² impart a rocking motion to the levers H and J, and at the same time impart a sliding motion to the said levers on the pivot pins I and I'. The crank arms G' and G² extend diametrically one relatively to the other so that the movement given to the front levers H is alternate, and in a like manner the movement given to the rear levers J is alternate, and the depending member H² of the lever H on one side of the frame or casing B moves forwardly and at the same time the depending member J² of the lever J on the other side of the frame or casing B moves forwardly while the depending member H² of the other front lever H is held against movement at its lower end and likewise the depending member J² of the other rear lever J. By locating the spring D in the rear portion of the frame or casing B the latter is slightly overweighted at its rear end relative to the front end thereof and consequently the depending members H² of the front levers H are lifted off the floor, table or other support during their forward swinging movement while the depending members J² of the rear levers J slide on the said support during their forward movement. It is understood that when the depending members H² and J² of the levers H and J have reached the end of their forward stroke they serve as fulcrums for moving the body A forward, the levers sliding on the pivots I and I'. It is understood that as the arms and legs of the baby or animal move with the depending members H² and J² of the levers a creeping or walking motion is given to the said bodies. By lifting the depending members H² and consequently the arms A' and the front legs A⁵ of the animated toy a ready forward progress is made as the pads A³, A⁷ are lifted clear of any slight obstruction that may be in the path. The pads A⁴ and A⁸ on the legs A² or the rear legs A⁶ are readily dragged in a forward direction over the surface and thus overcome any slight obstacle that may be in their path without causing the toy to come to a stop.

By the use of the train of gear wheels K to K⁸ above described a practically uniform speed is given to the crank shaft G to insure a uniform forward movement of the animated toy as long as the spring D is wound up.

Having thus described my invention, I claim as new and desire to secure by Letters Patent:

1. An animated toy provided with a positively driven crank shaft, levers arranged in pairs one pair on each side of the toy, the levers having depending members and longitudinally-extending members, the longitudinal members of each pair of levers being connected with the said crank shaft, and fixed pivots on which the said levers are mounted to swing and to slide. 75

2. An animated toy, comprising a body having movable limbs, a frame within the said body, a driven crank shaft journaled in the said frame, levers arranged in pairs, one pair on each side of the frame, the levers having depending members engaging the said limbs and the levers having longitudinal members connected with the said crank shaft, and pivots fixed on the said frame and on which the said levers are mounted to swing and to slide. 80

3. An animated toy, comprising a body having movable limbs, a frame within the said body, a driven crank shaft journaled in the said frame, levers arranged in pairs, one pair on each side of the frame, the levers having depending members engaging the said limbs and the levers having longitudinal members connected with the said crank shaft, the upper ends of the levers being provided with slots and pivots fixed on the said frame and engaging the said slots. 90

4. An animated toy, comprising a body, front and rear limbs pivotally and slidably mounted in the body, the rear limbs being bent and means for operating the limbs, the operating means being so arranged in the body as to overbalance the rear end relative to the front end, whereby the front limbs will be lifted and moved forwardly and the rear bent limbs dragged forwardly. 105

5. An animated toy, comprising a body having movable front and rear pairs of articulated limbs, a spring motor mounted in the rear end of the said body to overbalance the rear end relative to the front end of the body, a transverse crank shaft journaled on the said frame and driven from the said motor, and levers mounted to swing and to slide bodily on the said frame, the said levers being pivotally connected with the said crank shaft and rigidly with the said limbs to cause the rear limbs to drag over a support and the front legs to execute a step motion. 115

6. In an animated toy, a driven shaft having crank arms at its ends, and front and

rear pairs of pivotally and slidably mounted limbs, the limbs having projecting members rigid therewith and connected with the cranks of the shaft, the rigid projecting members of the limbs on the same side being connected with the same crank arm.

7. In an animated toy, a body, a driven shaft mounted in the body and having cranks at its ends, fixed pivots in the body, and front and rear pairs of limbs having rigid horizontal members connected with the cranks of the said shaft, the upper ends of

the front limbs having upwardly and rearwardly inclined slots and the rear limbs having upwardly and forwardly inclined slots, 15 the said slots receiving the pivot pins.

In testimony whereof I have signed my name to this specification in the presence of two subscribing witnesses.

ADOLF GUND.
